Inventor.

John F. Steward

UNITED STATES PATENT OFFICE.

JOHN F. STEWARD, OF PLANO, ILLINOIS.

GRAIN-BINDER.

SPECIFICATION forming part of Letters Patent No. 237,064, dated January 25, 1881.

Application filed November 1, 1880. (No model.)

To all whom it may concern:

Be it known that I, JOHN F. STEWARD, a citizen of the United States, residing at Plano, in the county of Kendall and State of Illinois, 5 have invented new and useful Improvements in Grain-Binders, of which the following is a full description, reference being had to the accompanying drawings.

The object of my invention is to make the 10 binding wholly automatic; and its nature consists in such an arrangement of the parts that the movement of the twine, as it passes from the ball to the needle or binding mechanism, may permit the clutch to engage at intervals, 15 and thus put the binding mechanism in motion and make the accumulating gavel regulate its own size.

My device may be applied to any of the well-known forms of automatic clutches in use, and 20 I do not confine myself to the one shown. It may also be used on any of the forms of binders now in use, but is shown as applied to those in which the grain is packed into the receptacle and against the twine or wire that is to 25 form the band.

Figure 1 is an end view of my invention, and Fig. 2 is a side view of the same.

In the drawings, A is a shaft from which the needle and tying mechanism are driven, 30 and which shaft makes one revolution to bind each bundle. B is a gear running loosely upon the shaft A, except when clutched thereto. Upon the hub of the gear B is the ratchet-wheel C. Keyed to the shaft A is the disk D. 35 Pivoted to this disk at F is the hooked pawl E, held in locking position by the spring G.

If the gear B revolves in the direction indicated by the arrow, the shaft A will be moved with it as long as the pawl remains engaged 40 with the ratchet-wheel C.

I is a rock-shaft journaled in bearings T on the sill S. H is a detent keyed on the rock-shaft I. J is a lever by which the shaft I is rocked. U is a spring coiled on the shaft I to 45 retain the detent H in an erect position, so as to be in the path of the extension of the pawl E.

If B is revolved in the direction indicated by the arrow, the extension of the pawl will soon reach the detent H, and as it draws upon 50 it the hook will be disengaged from the ratchet and the shaft will come to a state of rest, while

B continues to revolve. By lifting the lever J the detent will be thrown down and the pawl be permitted to engage with the ratchet, and the binding mechanism be carried through an 55 operation.

M is any shaft, or a special shaft that makes one revolution during each operation of the binder. It may be the shaft that operates the tyer. On this shaft is mounted the pulley N, 60 so that it may have about a half-revolution independent of the shaft. To confine this freedom within proper limits I put the arm O on the end of the shaft M and the pins P P on the pulley-wheel N. 65

L is a crank on the wheel N, and K a connecting-rod, slotted at Q so far that the crank may not act in a downward direction upon it.

N is a grooved pulley, and around it the twine is drawn from the ball to the needle and 70 tying mechanism. The pulley N may be a cone of several sizes, so that the passage of a greater or less amount of twine, as desired, will give it a rotation.

The operation of my invention is as follows: 75 The forcing of the grain against the twine that is to be carried around it (not shown) draws the same from the ball (not shown) in the direction indicated by the arrow at R and revolves the pulley N in the direction indicated, 80 and the crank L comes to the end in the slot Q of rod K, when the lever J will be lifted and the detent H be thrown downward, so that the pawl E will engage with the ratchet, and the shaft A, with the wheel B, be revolved, 85 and the binding mechanism be carried through one operation. This operation will be repeated as soon as the accumulating grain draws twine enough to move the pulley so far that the crank L shall lift the lever J and trip the 90 detent H again.

It is clear that for every revolution of the pulley a bundle will be bound, and that the size of the bundle will be regulated by the amount of twine required to give the pulley a 95 revolution; hence the size of the bundle will be equal to the size of the particular pulley of the cone that the twine passes around less the twine consumed in the knot.

The pulley N may be mounted on a stud in 100 any convenient position; but I prefer to have it as described, so that in case of breakage of

twine the pulley will still be carried, by the lever O striking the pin P, to its proper position of rest.

If something were not provided to determine this position of rest, the size of the first bundle, after threading up each time, would vary in proportion to the part of a revolution the pulley had to make before its crank reached the position for tripping.

10. The way of transmitting the movement of the pulley to the tripping device may be varied almost indefinitely, and I do not confine myself to any particular way.

The pulley N may be directly on the shaft 15 A, as it is mounted on M, and the parts so arranged that the crank L will come in contact with the detent H and move it out of the way of the pawl and permit it to engage with ratchet C.

20. What I claim as my invention, and desire to secure by Letters Patent, is—

1. The pulley N, in combination with the moving binding-cord and means for engaging and disengaging the binding mechanism, for the purpose specified, substantially as described.

2. The combination of the pulley N, connecting-rod K, detent H, and means for engaging and disengaging the binding mechanism, substantially as described, for the purpose 25 specified.

3. The shaft M, provided with the arm O, in combination with the pulley mounted loosely thereon, and provided with the stops P P', for the purpose specified, substantially as described.

JOHN F. STEWARD.
